UNITED STATES PATENT OFFICE.

FREDERICK J. OSIUS, OF RACINE, WISCONSIN.

MACHINE-MOTOR.

1,327,209.

Specification of Letters Patent.

Patented Jan. 6, 1920.

Application filed February 5, 1916. Serial No. 76,238.

To all whom it may concern:

Be it known that I, FREDERICK J. OSIUS, a citizen of the United States, and resident of Racine, in the county of Racine and

5 State of Wisconsin, have invented new and useful Improvements in Machine-Motors, of which the following is a description, reference being had to the accompanying drawings, which are a part of this specification.

10 This invention relates to improvements in machine motors more particularly adapted for actuating sewing or other light machines.

It is one of the objects of the present invention to provide a machine motor which may be easily mounted upon the arm of a sewing or other light machine and which when not in use may be swung to an out-of-the-way position beneath the arm of the machine in order to occupy the minimum amount of space when not in use and to permit the closing of the top or arm of the machine into the table top without removing the motor when said motor is used with a 25 machine of the drop head or foldable type.

A further object of the invention is to provide a machine motor which may be swung from one position to another with a minimum effort and which motor will be 30 automatically retained in either position.

A further object of the invention is to provide a machine motor in which the driving wheel of the motor is yieldingly held in engagement with the driven wheel of the 35 machine.

A further object of the invention is to provide a machine motor more particularly adapted for attachment to a Singer sewing machine and which motor may be so attached without in any manner marring, drilling or cutting attaching openings in the sewing machine and which will permit the closing of the arm or head into the table top without removing the motor.

45 A further object of the invention is to provide an electric motor which is of simple construction, is strong and durable and is well adapted for the purpose described.

With the above and other objects in view 50 the invention consists of the improved machine motor and its parts and combinations as set forth in the claims, and all equivalents thereof.

In the accompanying drawings in which the same reference characters indicate the 55 same parts in all of the views:

Figure 1 is a side view of a portion of a sewing machine arm with the improved electric motor attached thereto and in actuating position, the view also indicating by dotted 60 lines the motor in inoperative position beneath the arm of the machine;

Fig. 2 is a top view of the parts shown in Fig. 1;

Fig. 3 is a rear view of the sewing ma- 65 chine arm and the motor connected thereto; and

Fig. 4 is a horizontal sectional view taken on line 4—4 of Fig. 3.

Referring to the drawings the numeral 70 8 indicates in part the arm of a sewing machine of ordinary construction to which the improved electric motor 9 is attached. The arm comprises the upright column or standard 10 and the horizontally extending 75 portion 11 projecting from the upright and through which the horizontal driving shaft 12 extends and has its bearing. A hand or driven wheel 13 mounted on the rear end of the shaft 12 is yieldingly engaged and 80 driven by a grooved driving pulley 14 mounted on the armature shaft 15 of the motor 9. The wheel engaging portion of the pulley is preferably formed of cork or other like material to provide the necessary 85 frictional engagement between the pulley and the hand wheel.

Sewing machine arms of the Singer type are usually provided with a threaded opening 16 in the rear portion of the column 90 10 to permit the connection thereto of hand attachments for some trade. Advantage is taken of this threaded opening and it is utilized in connection with a screw 17 for attaching a curved bracket arm 18 thereto. 95 This bracket arm is curved to extend around a part of the upright column 10 and at its rear end is provided with an opening 19 through which the screw 17 extends, and at its forward end is provided with a bearing opening 20 which extends upwardly, forwardly and inwardly at an angle to receive the downwardly extending pivot pin 21 of the motor 9. The pin 21 is connected to and offset from the motor by an offset 105 arm 22 which is rigidly mounted on the

casing 23 of the motor. The pivot pin 21 is so inclined with relation to the sewing machine arm that when the motor is in actuating position the motor will be in upright position with its armature extending in a line parallel to the horizontal machine shaft 12 and on one side thereof, and when the motor is swung to an inoperative position it will be positioned directly beneath the horizontal portion of the sewing machine arm and at an angle thereto.

In order to hold the motor in both positions a coiled spring 24 is connected at one end to one of the motor casing bolts 25 and 15 at its other end is connected to an eyed projection 26 of the curved bracket arm 18. It will be noted that the motor in swinging from one position to the other will swing the outer end portion of the coiled spring 20 from one side of the pivot pin 21 to the other thus causing the spring to exert its tension to hold the motor in either position. The slight inward inclination of the pivotal connection also provides for the weight of the 25 motor exerting a tendency to maintain the motor in either position.

It will also be noted that the spring extends at a downward angle from the motor to the curved bracket to hold the two portions of the pivotal connection together.

When the motor is in actuating position the coiled spring will hold the motor driving pulley yieldingly in engagement with the hand or driven wheel of the sewing machine and when it is desired not to have the sewing machine actuated by the motor, the motor may be swung to a position beneath the sewing machine arm where it will be out of the way and it will occupy space not 40 ordinarily utilized.

Current is supplied to the motor by wires 27 and the speed of rotation of the motor is controlled in any manner desired.

From the foregoing description it will be 45 seen that the machine motor is of very simple construction and may be easily attached to a sewing machine.

What I claim as my invention is:

1. The combination of a frame consisting 50 in part of an upright portion and a horizontally extending portion supporting the wheel of the machine to be driven, a motor supporting bracket mounted on the upright portion, a motor and its shaft and a driving 55 wheel thereon, said motor being pivotally mounted on the bracket and movable to a position alongside of the horizontally extending portion to have its driving wheel drivingly engage the wheel of the machine 60 to be driven and movable to an inoperative position beneath the horizontally extending frame portion, and means for maintaining the motor in either one of its positions.

2. The combination of a frame consisting

in part of an upright portion and a horizontally extending portion supporting the wheel of the machine to be driven, a motor supporting bracket mounted on the upright portion, a motor and its shaft and a driving wheel thereon, said motor being pivotally mounted 65 on the bracket and movable to a position alongside of the horizontally extending portion to have its driving wheel drivingly engage the wheel of the machine 70 to be driven and movable to an inoperative position beneath the horizontally extending frame portion, and a spring means connected to the bracket and to the motor and positioned to be swung from one side of the 75 pivotal connection to the other to maintain the motor in either one of its positions.

3. The combination of a sewing machine arm and a hand wheel carried thereby, a bracket mounted on the arm, an electric motor and its shaft and a driving wheel 85 thereon, said motor being pivotally mounted on the bracket and movable to a position alongside of the arm to have its driving wheel drivingly engage the hand wheel and movable to an inoperative position beneath 90 the arm.

4. The combination of a sewing machine arm and a hand wheel carried thereby, a bracket mounted on the arm, an electric motor and its shaft and a driving wheel 95 thereon, said motor being pivotally mounted on the bracket and movable to a position alongside of the arm to have its driving wheel drivingly engage the hand wheel and movable to an inoperative position beneath 100 the arm, and a spring means connected to the bracket and to the motor to maintain said motor yieldingly in either one of its positions.

5. The combination of a sewing machine 105 arm and a hand wheel carried thereby, a bracket mounted on the arm, an electric motor and its shaft and a driving wheel thereon, said motor being pivotally mounted on the bracket and movable to a position 110 alongside of the arm to have its driving wheel drivingly engage the hand wheel and movable to an inoperative position beneath the arm, and a spring means connected to the bracket and to the motor and positioned to be swung from one side of the pivotal 115 connection to the other to maintain the motor in either one of its positions.

6. The combination of a sewing machine arm and a hand wheel carried thereby, a bracket mounted on the arm, an electric motor and its shaft and a driving wheel 120 thereon, said motor being pivotally mounted on the bracket and movable to a horizontal position alongside of the arm to have its driving wheel drivingly engage the hand wheel and movable to an inoperative oblique angular position with relation to the arm 125

and to a position beneath the arm, and means for yieldingly maintaining the motor in either one of its positions.

7. The combination of a sewing machine

- 5 arm and a hand wheel carried thereby, a bracket mounted on the arm, an electric motor and its shaft and a driving wheel thereon, said motor being pivotally mounted on the bracket and movable to a horizontal 10 position alongside of the arm to have its driving wheel drivingly engage the hand wheel and movable to an inoperative oblique angular position with relation to the arm and to a position beneath the arm, 15 and a spring means connected to the bracket and to the motor and positioned to be swung from one side of the pivotal connection to the other to yieldingly maintain the motor in either one of its positions.

- 20 8. The combination of a sewing machine arm and a hand wheel carried thereby, said arm having a threaded opening, a curved bracket positioned adjacent the arm and having openings in its opposite end portions, a screw extending through one of the bracket openings and into the threaded opening of the arm, the other opening of the bracket extending upwardly at an angle, an offset arm having a downwardly 25 projecting pivot pin which extends through the upwardly extending bracket opening, a motor mounted on said offset arm and having a shaft and a driving wheel thereon and movable to a horizontal position along- 30 side of the arm to have the driving wheel drivingly engage the hand wheel and movable to an inoperative angular position beneath the arm, and a spring means connected to the bracket and to the motor and 35 positioned to be swung from one side of the pivot to the other to yieldingly maintain the motor in either one of its positions.

9. The combination with a sewing machine having a base portion and a frame 45 portion and a wheel to be driven, of a motor supporting means mounted on the machine, and a motor member and its shaft and a driving wheel thereon mounted on the motor supporting means and movable 50 to a position to have its driving wheel drivingly engaging the machine wheel and movable to an inoperative position closer to the base of the machine.

10. The combination with a sewing machine having a base portion and a frame 55 portion and a wheel to be driven, of a motor supporting means mounted on the machine, an electric motor member and its shaft and a driving wheel thereon pivotally mounted on the motor supporting means and movable to approximately a horizontal position with its wheel engaging the machine wheel and movable to an inoperative position closer to the base portion and at

an angle to its operative position, and means for yieldingly maintaining the motor wheel in engagement with the machine wheel.

11. The combination with a sewing machine of a motor, a driving connection between the motor and the machine, means supporting the motor so that it may be moved into driving position or away therefrom and toward a position under the arm of the sewing machine frame, and means 75 for preventing the motor during its movement from engaging the sewing machine frame.

12. The combination with a sewing machine having a fly wheel of an electric motor having a friction drive wheel, means adapted to be attached to the end of the sewing machine frame to support the motor at the side of the frame so that the weight 80 of the motor tends to automatically maintain the drive wheel in engagement with the fly wheel of the machine, said supporting means permitting said motor to be moved from driving position to a position beneath the arm of the sewing machine 85 frame.

13. The combination with a sewing machine of an electric motor, means adapted to be attached to the end of the sewing machine frame to support the motor at the 90 side of the frame so that the weight of the motor automatically tends to maintain it in driving connection with said machine, said means permitting the motor to be moved from driving position to a position beneath 95 the arm of the sewing machine frame, and means associated with said first-named means for positively preventing the motor during its movement from contacting with the sewing machine frame.

14. The combination with a sewing machine having the usual frame structure above the bed plate, comprising a vertical standard and a horizontal arm, of a bracket adapted to be attached to the rear end face 110 of said standard and to extend to a point on one side of said frame structure, and a motor having a driving connection with said machine and supported by said bracket at said point.

15. The combination with a sewing machine having the usual frame structure above the bed plate comprising a vertical standard and horizontal arm, of a bracket adapted to be attached to the rear end face of said 120 standard and to extend to a point on one side of said frame structure, and a motor having a driving connection with said machine and supported by said bracket at said point so that the motor may be readily 125 moved from driving position to a position beneath said horizontal arm.

16. The combination with a sewing ma-

chine having the usual frame structure above the bed plate comprising a vertical standard and a horizontal arm and also having a fly wheel, of a bracket adapted to be attached to the rear end face of said standard and to extend to a point on one side of said frame, and an electric motor having a friction drive wheel supported by said bracket at said point so that the weight of the motor acts to automatically maintain said friction wheel in engagement with the fly wheel of the machine by the weight of the motor.

17. The combination with a sewing machine having an arm, of a motor, a driving connection between the motor and the machine, a fixed support, said motor being movably supported so that it may be moved into a position to make the driving connection or shifted on said support away therefrom and placed under said arm of the sewing machine.

18. The combination with a sewing machine having an arm, of a motor, a driving connection between the motor and the sewing machine, a bracket adapted to be attached to the sewing machine frame, said motor being pivoted to said bracket so that it may be moved from driving position to a position under said arm of the sewing machine.

19. The combination with a sewing machine having a fly wheel of a bracket adapted to be attached to the frame of the machine, a motor supporting arm pivoted to said bracket so that the arm may be moved both vertically and laterally to move the motor to and from its operative position, and a friction drive wheel carried by the motor shaft and adapted to engage the sewing machine fly wheel when the motor is in its driving position.

20. A supporting bracket adapted to be attached to a sewing machine frame having an arm, and a motor supporting arm piv-

oted to said bracket so that the motor may be moved from driving position to a position under the arm of the sewing machine frame.

21. A bracket adapted to be attached to a sewing machine frame having an arm, said bracket having a motor supporting arm movable both vertically and laterally so that the motor may be moved from a driving position to a position beneath said arm of the sewing machine frame. 55

22. The combination with a sewing machine having the usual arm and fly wheel of a bracket on the sewing machine, an electric motor movably supported on said bracket so that the motor drive wheel is automatically maintained in frictional engagement with the fly wheel of the machine, said bracket being also adapted to support the motor in position beneath said arm of the sewing machine. 60

23. The combination with a sewing machine having a base portion and a head portion and a wheel to be driven, of a motor supporting means mounted on the machine, and a motor member mounted on the motor supporting means in a position to have its driving pulley drivingly engage the machine wheel and movable to an inoperative and out of the way position closer to the base portion of the machine. 75

24. The combination with a sewing machine having a base portion and a head portion and a wheel to be driven, of a motor supporting means mounted on the machine, an electric motor pivotally mounted on the motor supporting means in position to have its driving pulley drivingly engage the machine wheel and movable to an inoperative position toward the sewing end of the machine. 80

In testimony whereof, I affix my signature.

FREDERICK J. OSIUS.
